UNITED STATES PATENT OFFICE

163,650

BED OR SIMILAR ARTICLE

Elliott White Springs, Fort Mill, S. C.

Application May 23, 1950, Serial No. 10,093

Term of patent 14 years

(Cl. D5—4)

To all whom it may concern:

Be it known that I, Elliott White Springs, a citizen of the United States, residing at Fort Mill, in the county of York, and State of South Carolina, have invented a new, original, and ornamental Design for a Bed or Similar Article, of which the following is a specification, reference being had to the accompanying drawing, forming part thereof.

The single figure in the drawing is a perspective view of a bed, showing my new design.

The side of the bed and the back of the headboard not visible in the single figure of the drawing are plain.

I claim:

The ornamental design for a bed or similar article, as shown and described.

ELLIOTT WHITE SPRINGS.
